UNITED STATES PATENT OFFICE

NORTON A. MEARS, OF CHICAGO, ILLINOIS, ASSIGNOR TO CHICAGO FORGING & MANUFACTURING COMPANY, OF CHICAGO, ILLINOIS, A CORPORATION OF ILLINOIS

HOOD LATCH

Application filed July 5, 1928. Serial No. 290,477.

My invention relates to a securing member which is particularly adaptable for use as a hood latch whereby an automobile hood or similar closure may be held in position. One 5 object of my invention is to provide such a latch which shall urge such a closure not only downwardly but laterally. Another object is the provision of such a latch which shall compensate for and conform to changes in 10 relation of the closure to the abutment against which it is thrust and which shall compensate for changes in the position of the latch engaging member on the closure. Another object is the provision of a device of the type 15 herein described which shall be cheaply manufactured and efficient in use. Other objects will appear from time to time in the course of the specification and claims.

I illustrate my invention more or less diagrammatically in the accompanying drawings, wherein—

Figure 1 is a side elevation;

Figure 2 is a section on the line 2—2 of Figure 1;

25 Figure 3 is a section similar to Figure 2 through a variant form of my device;

Figure 4 is a detail of the form of abutment shown in Figure 3;

Figure 5 is a section on the line 5—5 of 30 Figure 3;

Figure 6 is a vertical section through a further variant form;

Figure 7 is a section on the line 7—7 of Figure 6; and

35 Figure 8 is a vertical section through a further variant form.

Like parts are indicated by like symbols throughout the specification and drawings.

A generally indicates an automobile frame 40 and A¹ the lower portion of the hood. The lower edge of the hood abuts against an abutment herein shown as the channel member A² secured upon the base or frame A.

B generally indicates a latch abutment 45 adjustably mounted on the hood as by the bolts or rivets B¹ and the apertures B². The plurality of vertically aligned apertures permits a selection as to the initial location of the member B it not being generally necessary 50 after the device is installed to change its lo-

cation. In case of necessity, however, the apertures B² do permit of a change of location. B³ indicates an outwardly projecting lip or flange along the bottom of the member B. The member B³ is herein shown, as in Figure 1, as arcuate or rounded in cross-section both in a plane parallel with the face of the hood and in a plane perpendicular to it.

55 Referring particularly to Figures 1 and 2 C indicates a base member secured to the frame member A as by the bolts C¹ and nuts C². It includes the upwardly extending collar C³ which receives and holds the tube C⁴. Such a tube is inwardly upset at the top as at C⁵ to leave an aperture conforming generally 60 in shape and diameter to the pin D. The pin is provided at its bottom with a head D¹ and passes through a washer or abutment member D². The spring D³ is compressed between such washer and the head D¹ and tends 65 normally to draw the pin D downwardly towards the frame A in the dotted line position 70 shown in Figure 2.

Pivoted to the upper end of the pin D is 75 the combined handle and latch member generally indicated as E which includes the latch or toggle member E¹ the lower end of which, rounded as at E², is adapted to engage the abutment member B³ on the hood A¹. Associated with the toggle or latch member E¹ and herein shown as integral with it is the handle or finger ring E². The lower portion 80 of the member E, more or less squared as at E⁴, is adapted to engage the top of the tube C⁴ when the latch is released and takes the dotted line position shown in Figure 2.

85 Referring to Figures 3, 4 and 5, a variant form of the device is shown, the pin D being provided with the handle member generally indicated as G which includes the shroud G¹ surrounding the upper end of the tube, the handle portion proper G² and the laterally projecting lug G³. Pivoted to said lug is 90 the toggle or lever G⁴ with the rounded end G⁵ adapted to engage the abutment member B³. G⁶ indicates a coil spring adapted normally to yieldingly move the member G⁴ toward the side of the hood A¹ and away from the shroud G¹ when it is released from the abutment B³.

A variation of the end G^5 of the member G^4 is shown, which is also applicable to the member E^1 shown in Figures 1 and 2. It is provided with a central notch or channel H adapted to seat upon a ridge or projection H^1 formed in the abutment member B^3 .

Referring to Figures 6 and 7 I illustrate a variant form of my device in which the handle member J is secured to the top of the pin D and is provided with a lug or plurality of lugs J^1 through which passes the pivot pin J^2 to which are pivoted the arms J^3 which join to form the latch or toggle member J^4 the lip or end J^5 of which is adapted to engage the abutment member B^3 . J^6 indicates a spring or similar yielding means tending normally to hold the latch in the position shown in Figure 6.

Figure 8 indicates a further variant form in which in the place of the fixed cylindrical guide C^4 of the other forms the pin K is fixed in the base member K^1 and is therefore normally rigid in relation to the frame A . The pin K is provided at its upper end with an enlargement K^2 adapted to act as abutment for the spring L .

L^1 indicates a cylinder surrounding said pin and spring and provided at the bottom with the inturned portion L^2 which serves to hold the washer or spring abutment L^3 . The normal effect of the spring L is to move the cylinder L^1 downwardly along the pin K . Secured to the upper end of the cylinder L^1 is the head portion L^4 herein shown as surrounding the end of the tube or cylinder. It includes the upwardly extending lugs L^5 to which is pivoted the toggle member L^6 to which is associated the handle or finger ring L^7 . L^8 is a flat spring opposed to the portion L^9 of the handle member and is adapted normally to urge it into the dotted line position shown in Figure 8, when it is withdrawn from the abutment B^3 .

It will be realized that whereas I have described and shown a practical and operative device, nevertheless many changes might be made in the size, shape, number and disposition of parts. I therefore wish my description and drawings to be taken as in a broad sense illustrative and diagrammatic rather than as limiting me to my specific showing.

The use and operation of my invention are as follows:

Stated generally the general characteristic of my invention is the employment of a guide, the tube C^4 or the pin K , which projects upwardly in generally fixed position on the frame A . It may be parallel with the face of the hood A^1 or it may be inclined thereto, but it is preferable that whatever its relation, it be a constant relation, the tube or pin serving as a fixed guide. Upon such fixed guide I position a movable element, the pin D of Figures 1 to 7 or the cylinder or tube L^1 of Figure 8. Upon this movable member

I position a lever or latch or toggle which is in flexible or pivotal relation with the moving member. The length of such latch member must exceed the distance between the movable member and guide and the opposed abutment B^3 on the hood. Since the spring D^3 or L tends to urge the movable tube or pin downwardly along the fixed guide and since the pivot of the latch is positioned substantially above the point of engagement between the inside end of the latch and the abutment on the hood, the downward movement of the movable member tends not only to exert a downward thrust against the member B^3 but also to direct a lateral thrust. When, in response to such downward thrust the hood is moved as far downwardly as it can, further downward movement of the movable member tends to clamp the hood inwardly against the abutment A^2 and when this movement is effected, no further downward movement is possible. Rattle and displacement is prevented and the lower edge of the hood is firmly but yieldingly locked against the abutment A^2 .

There are many variations possible without departing from the spirit of my invention and I have illustrated a fixed tube as a guide for a movable pin and a fixed pin as a guide for a movable tube. I have also shown, as in Figures 1, 2 and 8, a combined handle and latch member pivoted to a movable pin or tube, whereas in Figures 3, 5, 6 and 7 I have illustrated handle members fixed in relation to the movable member, the latch member being pivoted to the handle member or to the movable member. In all cases the general principle of operation is identical, the downward movement of the movable member causing both downward and inward pressure against the hood.

I find it under some circumstances preferable to provide yielding means for withdrawing the latch from alignment with the abutment B^3 when the latch is released. In the form of Figure 2 the spring D^3 has this effect, drawing the portion E^4 of the handle member down against the top of the tube C^4 . In Figures 3, 5, 6, 7 and 8 I employ separate spring means tending to withdraw the latch member when released. I may, if I wish, dispense with such means, particularly in the forms wherein the latch and handle are united. In such case when the handle is upwardly drawn to release the latch the handle and latch may be rotated out of alignment with the abutment B^3 , the fixed member and the movable member being preferably not held against rotation.

I claim:

1. In combination, a closure having a latch engaging means thereon, a generally fixed guide positioned adjacent said closure member, a movable member axially movable in

- relation to said guide, yielding means for urging it downwardly along said guide, a latch member pivoted to said movable member, the outer end of the latch member being 5 adapted to engage the latch engaging means on the closure member, the length of said latch member from pivot point to end being more than the distance separating the pivot point and the opposed closure, the point of 10 engagement of the latch member with the opposed latch engaging means being spaced laterally from the path of movement of the movable member, and toward the closure, and additional yielding means for withdrawing 15 said latch member from said closure when released from said latch engaging means.
2. In combination, a closure having a latch engaging means thereon, a fixed tubular guide positioned adjacent said closure member, a pin axially movable in said guide, a spring, compressed between said guide and pin and adapted normally to move said pin downwardly in relation to said guide, and a 20 unitary handle and a latch member pivoted to the upper end of said pin exteriorly of said guide, the point of engagement of the latch member with the opposed latch engaging means being spaced laterally from the guide, and toward the closure.
3. In combination, an automobile hood having a latch engaging means thereon, a member, mounted adjacent to but laterally spaced away from said hood, and means for constraining such member to movement along 30 a generally upright axis adjacent the face of said hood, a unitary handle and a latch member pivoted to said movable member, the outer end of the latch member being adapted to engage the latch engaging means on the 35 hood, the length of said latch member from pivot point to the hood engaging end being greater than the distance separating the pivot point and the hood, said pivot point being laterally outwardly spaced from the point 40 of engagement of latch member and hood.
4. In combination, an automobile hood having a latch engaging means thereon, a member, mounted adjacent to but laterally spaced away from said hood, and means for constraining such member to movement along 45 a generally upright axis adjacent the face of said hood, including a normally rigid guiding member mounted adjacent the automobile hood, a unitary handle and a latch member pivoted to said movable member, the outer end of the latch member being adapted to engage the latch engaging means on the 50 hood, the length of said latch member from pivot point to the hood engaging end being greater than the distance separating the pivot point and the hood, said pivot point being laterally outwardly spaced from the point 55 of engagement of latch member and hood.
5. In combination, an automobile hood 60 having a latch engaging means thereon, a member, mounted adjacent to but laterally spaced away from said hood, and means for constraining such member to movement along a generally upright axis adjacent the face of said hood, a unitary handle and a latch member pivoted to said movable member, the outer end of the latch member being adapted to engage the latch engaging means on the 65 hood, the length of said latch member from pivot point to the hood engaging end being greater than the distance separating the pivot point and the hood, said pivot point being laterally outwardly spaced from the point of engagement of latch member and hood.
6. In combination, an automobile hood 70 having a latch engaging means thereon, a member, mounted adjacent to but laterally spaced away from said hood, and means for constraining such member to movement along a generally upright axis adjacent the face of said hood, a unitary handle and a latch member flexibly mounted upon said movable member, the outer end of the latch member being adapted to engage the latch engaging means on the 75 hood, the length of said latch member from its point of connection with the movable member to the hood engaging end being greater than the distance separating the pivot point and the hood, the connection between the latch member and the movable member being laterally outwardly spaced from the point of engagement of latch member and hood.
